WISCONSIN

CONSTANT LEVEL SAFETY DEVICE FOR LIQUID FUEL LIGHTERS

Application filed February 11, 1929. Serial No. 339,168.

This invention relates to a novel constant level safety device for liquid fuel lighters.

One of the objects of our invention is the provision of a device whereby to not only maintain a constant level for the fuel feeding of a liquid fuel lighter, but provides means whereby the fuel supply to the lighter is limited so that even though the feed valve be left open after use, only a small amount of fuel will be delivered therethrough and means is provided whereby this small amount will be conducted into the main burner tube so as to eliminate waste and danger of the fuel igniting.

Another object of our invention is the provision of a constant level safety fuel feeding device wherein there is provided a constant level cup arranged within the main fuel tank, whereby a small amount of fuel may be used for feeding the lighter for fuel burners and the contents of the cup is replenished from the main supply of fuel, thus the feeding of the fuel to the lighters is limited to the quantity in the cup and this small quantity flowing into the lighter when the lighter is not burning will be directed into the main burner tube so as to be absorbed into the fuel used in the burner and not wasted as done heretofore.

Another object of our invention is the provision of a device of the above character which can be quickly and readily installed and used in connection with various types of liquid fuel burners in use on the market at the present time.

Another object of our invention is the provision of a novel type of wet vapor instantaneous lighter wherein means is provided for draining the liquid fuel from the burner cup when the lighter is not in use, should any of the fuel be fed into the cup when the burner is not lighted.

A further object of the invention is the provision of a novel type of lighter for gaseous fuel burners having in connection therewith novel means for draining liquid fuel from the burner cup into the main fuel tube of the burner so as to prevent the burner cup of the lighter from overflowing and

creating waste of the fuel and danger of igniting.

With the above and other objects in view, the invention consists in the novel features of construction, the combination and arrangement of parts hereinafter more fully set forth, pointed out in the claim and shown in the accompanying drawings wherein:

Figure 1 is a sectional view of an improved liquid fuel burner constructed in accordance with our invention, said view being taken on the line 1—1 of Figure 2;

Figure 2 is a transverse section taken on the line 2—2 of Figure 1; and

Figure 3 is a side elevation of a liquid fuel tank illustrating our improved constant level device applied thereto.

Referring more particularly to the drawings wherein we have illustrated our improved device, it will be noted that the burner is illustrated in Figures 1 and 2.

The burner includes the main tubular body 1 having outlets 2 which communicate with the burners 3, communication with the burners being controlled by means of the valves 4, having the usual valve stems 5 and hand grips 6.

The generator tube 7 is supported above and in alignment with the body 1 and beneath the tube is the generator burner 8 which communicates with the main body 1 through the tubular portion 9 and the flow of gas to the burner 8 is controlled through one of the valves 4 so that when one of the burners 3 is ignited the supply of gas is admitted to the generator burner 8.

The body 1 is provided with an upwardly curved tubular portion 10, the extremity of which extends parallel with the body 1 and one end of the generator tube 7 extends into the curved tube 10 as shown in Figure 1.

The end of the tube 10 is provided with a vertical inlet portion 11 for supplying air to the generated gas as it passes from the tube 7 into the body 1. The tube 7 is provided with a T—12 having a conduit 13 leading therefrom and communicating with the bottom of the fuel tank 14 as shown in Figure 3.

Extending upwardly from the body 1 is 100

a supporting flange 15 to which is attached the bracket 16 supporting the fuel burner cup 17 of the lighter. Extending downwardly and opening into the bottom of the cup 17 is a tubular bore 18, housing a conduit 19 which leads into the body 1 at the upper side thereof as illustrated in Figure 2, so that the ungenerated fuel accumulated in the cup 17 may be passed into the body 1 and mixed with the fuel so as to be generated before conducted to the burners 3. Extending from one side of the cup 17 and communicating therewith is a U-shaped passage 20 communicating at its outer end with the generator tube 21 for the lighter. The tube 20 communicating with the atmosphere adjacent the inner end of the tube 21 by means of an inlet port 22 which admits air to the tube 20 to be mixed with the fuel passing from the tube 21, through the tube 20 to the cup 17.

The tube 21 is connected by means of a conduit 23 to the chamber 24 located within the supply cup 25 positioned within the tank 14 at the top side thereof as shown in Figure 3.

When it is desired to use the device, the valve 26 which controls a supply of gas from the cup 25 to the lighter generator tube 21 is opened and the fuel under pressure passes through the tube 20 until a supply is within the cup 17, it is ignited and the heat therefrom will generate the fuel within the tube 21 into gas, the gas passing through the tube 20 into the cup 17 where it will burn upwardly heating both the tubes 21 and 7.

After the tube 7 has been heated to the proper degree, the valve 12 is opened to admit fuel to the tube 7 for generation. If desired, one of the valves 4 to the burners 3 may be opened prior to the opening of the valve 12 or immediately following, as the fuel when it reaches the tube 7 after passing through the valve 12, will be immediately generated and directed into the curved tube 10 where upon its first entrance thereto is mixed with air entering through the inlet 11, the gaseous fuel entering the body 1 and passes through one of the tubes 2 to one of the burners 3.

It will be noted that after the valve 26 has been closed, any unburned fuel within the cup 17 will be drained down through the conduit 19 into the main body 1 where it will be mixed with the fuel therein and carried to the burners 3.

In a great many instances, the fuel cups or receptacles for the lighter are overflowed through the negligence of persons operating the burner by leaving the fuel control valve open, permitting the fuel to drain into the cup and this not only causes danger and great annoyance, but loss of fuel. This objection, however, is overcome in the present

instance, as any fuel from the supply cup 25 within the tank 14 draining into the burner cup 17, will be immediately carried off into the body 1 through the conduit 19.

Furthermore, in the present instance, with the construction of our device, only a certain predetermined amount of fuel could possibly be conveyed to the cup 17, as the cup 25, which will be known as the constant level cup, contains at one filling a certain amount of fuel and after this has been drained off through the chamber 24, the supply within the cup cannot be replenished until it is desired to start the burner.

In order to keep the supply within the cup 25 replenished, we connect up the cup 25 with the valve 27, by means of a tube 28, which leads into the cup 25 at a point above the fuel level. The fuel level in the present instance, is controlled by means of an outlet 29 so that only a predetermined amount of fuel will be maintained with the cup 25.

In order to supply the fuel to the cup 25, the tube 28 is looped downwardly so that its intermediate portion is arranged adjacent the bottom of the main tank 14 and is provided at this point with an inlet opening 30 which permits the fuel to enter the tube 28 and to be carried upwardly into the cup 25. The fuel is forced into the cup 25 through operation of a pump connected to the valve 27 through the conduit 31 or this conduit 31 may be connected to a source of air under pressure for not only supplying air pressure to the tank 14 but can be used for forcing the fuel from the tank 14 into the cup 25.

The air pressure within the cup 25 is maintained through the tube 28, as this tube is provided at a point adjacent the valve 27 with an inlet 32, communicating with the air pressure of the tank 14 above the fuel therein, this inlet 32 also preventing the fuel from backing up from the tank 14 to the pump or to the air supply when the valve 27 is opened.

It will be apparent from the foregoing that by providing the cup 25 to maintain a constant level for the lighter, it will provide a feeding means for the burner which supplies the proper amount of fuel for the lighter during its use in heating the generator 7 and should the valve 26 be allowed to remain open at any time, the amount of fuel drained from the cup 25 will not remain in the cup 17, but will pass downwardly into the body 1. It will be noted that with the use of our improved device, a constant level is maintained for the fuel feeding of the lighter and at the same time the fuel supply to the lighter is limited and any ungenerated liquid fuel will not be wasted. As shown in Figure 2, the valve member 26 is supported upon an arm 33 which is illustrated as angular in shape with one end thereof connected to the bracket 16. This forms a rigid support for the valve 26 and

will maintain the inner end of the tube 21 connected up with the passage 20.

We claim:

In a constant level safety device for liquid fuel lighters, a supply and storage tank, an auxiliary supply tank carried by the top wall of the main supply storage tank, and arranged within the main tank and depending from said top wall, said auxiliary supply tank being normally arranged above the fuel level in the main tank, an outlet fuel pipe leading from the auxiliary supply tank, and a pipe for feeding air under pressure extending into the main tank and having a loop provided with an opening arranged adjacent the bottom of the tank, the inner end of said pipe extending into the auxiliary supply tank above the liquid level thereof.

In testimony that we claim the foregoing we have hereunto set our hands at Milwaukee, in the county of Milwaukee and State of Wisconsin.

JOSEPH SLADKY.
ALEXANDER C. SLADKY.
